DESIGN FOR A PENCIL SHARPENER

Edward C. Hoffmann, University City, Mo., assignor to Triple "E" Products Co., St. Louis, Mo., a corporation of Missouri

Application January 5, 1940, Serial No. 89,307

Term of patent 14 years

To all whom it may concern:

Be it known that I, Edward C. Hoffmann, a citizen of the United States, residing in University City, St. Louis County, State of Missouri, have invented a new, original, and ornamental Design for a Pencil Sharpener, of which the following is a specification, reference being had to the accompanying drawing, in which:

Fig. 1 is a top plan view of a pencil sharpener embodying my new design; and,

Fig. 2 is a perspective view thereof.

The characteristic feature of my new design for a pencil sharpener resides in the backwardly and downwardly curved lines of the main body.

I claim:

The ornamental design for a pencil sharpener, as shown and described.

EDWARD C. HOFFMANN.
